SHRUB CUTTER

James J. Zimmerman, Kansas City, Mo.

Application November 10, 1938, Serial No. 239,883

5 Claims. (Cl. 56—233)

This invention relates to an improved cutter for shrubbery, which is particularly adapted for trimming hedges.

- More particularly, it is an aim of this invention to provide a manually operated shrub cutter of the reciprocating type having means for mounting the cutter at a predetermined height so that the hedge or shrubbery to be trimmed will be cut to a uniform height.
10. More particularly, it is an aim of this invention to provide a cutter comprising reciprocating cutting bars having means for manually moving one of said cutter bars, in one direction relatively to the other cutter bar, and spring means for returning said cutter bar to its original position to thereby impart a reciprocating motion thereto.

Still a further aim of the invention, is to provide a post on which the cutting element may be adjustably mounted, said post having means 20 at one end for embedding it in the earth to a predetermined depth, and means on the opposite end for revolving the post to revolve the cutting element.

Other objects and advantages of the invention 25 will hereinafter become more fully apparent from the following description of the drawing, which illustrates a preferred embodiment thereof, and wherein:

Figure 1 is a top plan view of the invention, 30 Figure 2 is a vertical sectional view taken along the line 2—2 of Figure 1.

Figure 3 is a transverse vertical sectional view taken along the line 3—3 of Figure 1, and

Figure 4 is a horizontal sectional view taken 35 along the line 4—4 of Figure 2.

Referring more particularly to the drawing, wherein like reference characters designate like or corresponding parts throughout, 10 designates generally a post which is provided with the pointed lower end 11 and the annular outwardly projecting flange 12 adjacent said end. Post 10 is preferably calibrated in feet, as indicated at 13, and is provided at its opposite end with an enlarged head forming the handle 14. Head 14 is preferably provided with an internally threaded bore to removably engage the reduced threaded upper end of the post 10, as seen in dotted lines in Figure 1, so that cutter 15 may be removed when the device is stored.

50 A reciprocating cutter, designated generally 15, comprises the lower cutter bar 16 and the upper cutter bar 17. Cutter bar 17 at one end is elongated and provided with the socket 18 disposed transversely thereto to slidably engage the shank 55 of the post 10. A set screw 19 is mounted in the

socket 18 to adjustably secure it relatively to the post. This elongated end 20 of the bar 17 is also recessed at 21 to receive a conventional liquid level gauge designated 22. The bar 17 adjacent its ends is provided with threaded openings 23 and intermediate of its ends with the longitudinally disposed recess 24.

The upper cutter bar 16 is provided with the depending flange 25 intermediate of its ends, which fits into the recess 24, and which as seen in Figure 2 is of a length substantially less than that of the recess. The width of the recess 24 is just sufficient to slidably mount the flange 25. Bar 16 is also provided with the longitudinal slots 26, adjacent its opposite ends, through which extend the bolts 27 which engage the threaded openings 23 in the bar 17 to connect the cutting bars. It will thus be seen that the cutting bars 16 and 17 are slidably mounted relatively to each other by means of the bolts 27 which slidably engage the slots 26 and the flange 25 which slidably engages recess 24.

A pair of eyebolts 28 and 29 are mounted in and project upwardly from the bar 16, between the slots 26 and adjacent thereto. To the eyebolt 25 29, which is disposed adjacent to the post 10, is connected a chain 30 having a handle 31 at its free end. A contractile coil spring 32 is connected at one end to the eyebolt 28 and at its opposite end to the bolt 27 adjacent thereto and this 30 spring normally holds the bar 16 in a retracted position or away from the post 10, as seen in Figures 1 and 2.

Bar 16 is provided, along one of its longitudinal edges, with the row of outwardly projecting 35 spaced cutting teeth 33, which are pointed at their free ends, as seen at 34, and which are beveled on their upper sides and along the left side of each tooth to provide the cutting edges 35. Teeth 33 are removably secured to the bar 16 by the 40 fastenings 36, which may be in the form of rivets. Cutter bar 17 along its corresponding edge is provided with the outwardly projecting teeth 37 which are beveled along their underside and at their right edges, not shown, to provide the cutting edges 38 to co-act with the cutting edges 35 of teeth 33 when the bar 16 is moved toward the post 10. Teeth 37 are likewise secured to bar 17 by corresponding fastenings 36, and as seen in Figure 3, bars 16 and 17 are provided with the 50 recesses 39 in which the teeth 33 and 37 seat and by means of which they are prevented from turning relatively to the bars 16 and 17 while secured thereto.

From the foregoing it will be seen, that the 55

pointed end 11 of the post 10 may be driven into the earth up to the flange 12 and it is intended that for example, in cutting hedges, that the post 10 be disposed between the opposite sides of 5 the hedge after which screw 19 may be loosened to adjust the cutter 15 to the desired height, at which the hedge is to be cut, as indicated by the calibrations 13, after which the screw is tightened to clamp socket 18 to the shank of the 10 post 10. The operator will preferably grasp the handle 14 with one hand and the handle 31 with the other and by pulling on handle 31 draw the cutter bar 16 toward the post 10 so that the cutting edges 35 and 38 of the teeth 33 and 37, respectively, will be caused to co-act in the usual manner to cut the shrubbery. When bar 16 has reached its fully projected position, as seen in Figure 4, the pressure on chain 30 is released to allow the spring 32 to return bar 16 to its retracted position, as seen in Figure 1, in which position the teeth 37 are disposed directly beneath the teeth 33. This operation is continued to impart a reciprocating motion to the bar 16, and simultaneously therewith, post 10 is slowly 25 revolved to revolve the cutter 15. In this manner, a circular cut can be made after which the portion of the hedge between the bars 16 and 17 and the post 10 may be cut by moving the post slightly. This operation is continued until the 30 top of the whole hedge has been trimmed, and it will be noted that by embedding point 11 each time to flange 12 the top of the hedge will be cut to the same height throughout its length and to further insure leveling the hedge post 10 may 35 be adjusted until the gauge 22 is centered. After the top of the hedge has been cut post 10 is positioned horizontally above the hedge with the cutter 15 disposed at one side thereof and operated in this manner for trimming the sides of 40 the hedge. The device is also intended for use in trimming other shrubbery in a similar manner.

Various modifications and changes in the construction and arrangement of the parts forming the invention are contemplated and may obviously be resorted to, and the right is therefore expressly reserved to make such changes as fall within the spirit and scope of the invention as hereinafter defined by the appended claims.

I claim as my invention:

50 1. A shrub cutter comprising a pair of cutter bars reciprocally mounted relatively to each other and provided with interacting cutting teeth, manual and spring means for imparting a reciprocating motion to one of said cutter bars relatively to 55 the other cutter bar, a post for supporting the cutter bars, said last mentioned cutter bar being provided with an elongated end having means for adjustably attaching it to said post, and said post having a pointed end to engage the earth 60 and a handle on its other end for turning the post to swing the cutter bars in substantially a horizontal plane.

65 2. A hedge trimmer comprising a post having means for embedding one of its ends in the earth to a predetermined distance to mount the post

in an upright position, the shank of said post being calibrated in feet, cutting means comprising a pair of cutting bars, one of said cutting bars having an elongated end provided with a socket and set screw for adjustably mounting it on said post and at substantially a right angle thereto, said other cutting bar being reciprocally mounted relatively to said first mentioned cutting bar, manual means for moving said last mentioned cutting bar in one direction, contractile spring 10 means for moving the cutting bar in the opposite direction and for co-acting with said manual means for imparting a reciprocating motion to said last mentioned cutting bar, and a handle on the opposite end of the post for turning it to swing the cutting means in substantially a horizontal plane with the post as an axis.

3. A device as in claim 2, said post embedding means comprising a pointed end adapted to be driven into the earth and a flange adjacent said end for limiting the depth to which the post can be embedded.

4. In a shrub cutter, a post having one end tapered to a point to be driven into the earth, a flange adjacent said end to limit the depth to which the end can be embedded and to retain the post in substantially an upright position; a cutter comprising upper and lower cutter bars provided with co-acting teeth along their corresponding leading edges, the lower cutter bar being elongated, at one end, to extend beyond the upper cutter bar, said end having a socket, for slidably engaging the post, a set screw for adjustably clamping the socket relatively to the post for supporting the cutter thereon, means for slidably mounting the upper cutter bar on the lower cutter bar, a handle connected to the upper cutter bar, a contractile spring connected to the upper and lower cutter bars; said handle and spring forming a combined manual and automatic means for reciprocating the upper cutter bar; and a knob on the opposite end of the post for turning the post to revolve the cutter in substantially a horizontal plane with the post as its axis.

5. A device as in claim 4, the teeth of the lower cutter bar having substantially parallel opposite edges and outer ends disposed substantially at right angles thereto, a corresponding longitudinal edge of each tooth being beveled on its underside to form a cutting edge, and the teeth of the upper cutter bar having corresponding spaced substantially parallel longitudinal edges, said edges being tapered to a point beyond the ends of the teeth of the lower cutter bar, each of said upper teeth having a longitudinal edge beveled on its upper side to form a cutting edge, the cutting edges of the teeth of the upper cutter bar being on the opposite side to the cutting edges of the teeth of the lower cutter bar, and the teeth of the lower cutter bar being disposed beneath the teeth of the upper cutter bar when the bars are in a normal, idle position.

JAMES J. ZIMMERMAN.
